WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

SET-BAR MECHANISM FOR PERFORATING-MACHINES.

1,307,682.

Specification of Letters Patent. Patented June 24, 1919.

Application filed November 20, 1917 Serial No. 202,908.

To all whom it may concern:

Be it known that I, WILLIAM W. LASKER, a citizen of the United States, residing in borough of Brooklyn, in the county of Kings 5 and State of New York, have invented certain new and useful Improvements in Set-Bar Mechanisms for Perforating-Machines, of which the following is a specification.

This invention relates to machines for perforating cards for use in accounting machines or for other purposes.

One of the main objects of the invention is to provide improved actuating mechanism in which, in a single row of perforating 15 punches, only one punch will be actuated at a time to the exclusion of the others, in which the actuation of a second punch in the same row will surely release the punches previously actuated in such row.

Other objects of the invention are to provide means for automatically releasing before the punches are reset for punching the next card, all or a part of the punches which have been previously set.

Another object of the invention is to provide means for holding certain of the punches in operative position during and throughout the punching of a series of cards, without having manually to reset such 30 punches for each card of the series.

These and other objects, capabilities and advantages of the invention will appear from the subjoined detailed description of one embodiment of the invention, illustrated 35 in the accompanying drawings, in which:

Figure 1 is a sectional view of a perforator equipped with the present improvements;

Fig. 2 is a fragmental sectional view, 40 showing the punch setting mechanism;

Fig. 3 is a fragmental end elevation of the punch setting mechanism;

Fig. 4 is a fragmental elevation partly in section showing punch setting bars in different positions of adjustment;

Fig. 5 is a side elevation of one of the setting bars;

Fig. 6 is an edge elevation of the same;

Fig. 7 is a plan of a latch bar for latching the setting bar in said position of adjustment, and

Fig. 8 is an edge view of the latch bar.

In the illustrated embodiment of my invention there is provided a main frame M 65 having secured at one end a card hopper C

from which the cards to be perforated are fed to a position between the die plate 12 and the punch guide plate 13 to coöperate with punches 14 mounted in the perforations of the guide plate 13 with their heads 15 normally resting on the plate 16. From the plates 12 and 13 the cards are discharged into the receptacle 17 after having been perforated. The plates 12 and 13 are adapted to be vertically reciprocated so that 60 the punches 14 may coöperate with the setting pins 18 to punch the card, in which operation the punches 14 which have no setting members such as the pins 18 or setting bar 19 depressed in alinement with them will rise with the plates 12 and 13 while those punches 14 which are obstructed in their upward movement by depressed setting pins 18 will perforate the card. For 70 each punch 14 there is provided a setting pin 18 disposed in alinement with and directly above the same.

Above each setting pin 18, is vertically 80 slidably disposed a setting bar 19 mounted and guided in the alined openings of plates 20 carried on cross pieces 21, on which cross pieces there are carried a pair of end plates 22. On each pin 18 there is provided a collar between which collars and the lower plate 23 the springs 24 are strained, whereby the pins 18 and the bars 19 are yieldably held in raised position. Along the edge of the bars 19 there is provided an upper recess 25 and a lower recess 26 which provide an upper abutment shoulder 27, a lower cam face 29 and a connecting rounded upper cam face 30 merging into said upper shoulder and said lower cam face.

Said recesses 25 and 26 coöperate with latching shoulders 32 provided on the teeth 33 of the anchoring means such as the latch bars 34 slidably mounted in openings in the lower part of said end plates 22.

The recesses 25 and 26 of each row of bars 19 face in the same direction, a latch bar 100 being provided with each row of bars 19 so that a single latch bar may coöperate with the recesses of all the bars of that particular row.

The latching shoulders of the latch bars 105 34 are normally maintained in contact with the bars 19 by means of springs 36 held in place upon the outer face of one of the end plates 22 by means of the clamping plate 28, the ends of said springs engaging in per-

forations 39 in the ends of the latch bars. For setting bars 19 and the pins 18, a transversely movable carriage 43 is provided on which key actuated plungers 44 are mounted. The carriage 43 is actuated across said bars 19 in a step by step movement so that its rows of plungers 44 successively register with the rows of bars 19.

In the operation of the machine with every actuation of a plunger 44, a bar 19 will be depressed in that row of setting bars which is in registration with the plungers 44, which bar 19 upon being depressed will thrust the associated latch bar endwise until the shoulder 32 enters into the upper recess 25 and over the upper shoulder 27 of such depressed bar. The latching shoulder 32 normally engages in the lower recess 26.

Immediately after such bar 19 is depressed, the plunger 44 is released and the carriage advanced so that the plungers 44 will register with the next succeeding row of bars 19. This advance of the carriage 44 will continue until the entire record has been set for perforation, whereupon the plates 12 and 13 will rise so that the punches 14 will be raised, except those that are obstructed by depressed bars 19 and depressed pins 18, whereupon the obstructed punches will perforate the card to produce a corresponding record thereon, while those punches 14 which are in alignment with bars 19 and pins 18 which have not been depressed, will rise with the card.

Whenever a bar 19 is depressed and the lower cam face 29 pushes back the shoulder 32, any shoulder 32 which has been previously in engagement with an upper shoulder 27 will be released, the shoulder 32 passing to the rounded cam face 30, whereupon upward movement of the bar 19 induced by the spring 24 will cause the cam face 30 to force the latching shoulder 32 fully back, so that there will be no danger that the said previously depressed setting bar will not be released. By this arrangement extreme accuracy in the construction of the latching shoulders 32 and the upper cam face 30 is not necessary, since whenever a setting bar 19 becomes depressed the latching shoulders must be thereby pushed back as far as the extreme outer point of the upper cam face 30, while in order to release any previously depressed setting bar it is only necessary that the latching shoulder 32 be pushed back far enough to clear the upper shoulder 27.

It will be seen that from the above arrangement it is impossible for two setting bars of the same row to remain depressed at the same time, since the depression of any latch bar will surely release all other depressed bars of the same row. By this arrangement a wrongly depressed setting bar is automatically released on the actuation 5 of the proper setting bar.

Upon the carriage 43 and constituting releasing means, there is pivotally mounted a bracket 46 yieldably pressed by means of the spring 47 toward the perforated ends of the latch bars 34, the lower end of said bracket being provided with a roller 48 adapted to press against said ends and yieldably overcome the tension of the springs 36 and release all of the setting bars as the carriage is moved forwardly or backwardly. Said roller is located forwardly of the transverse vertical plane passing through said plungers 44 so that as the carriage moves forward no setting bar which has just been set will be released, but any setting bar which may have been accidentally previously depressed will be released, and all of the setting bars will be depressed on the rearward return of the carriage after a card has been punched.

It is often desirable in certain operations that certain combinations of punches and their setting bars remain depressed so that corresponding combinations of holes be punched on every card throughout the whole series without the necessity of resetting the punches for each card in the ordinary manner. To this end, I have provided locking keys 50 in alignment with the respective latch bars 34 and slidably toward or away from the rack bars and frictionally held in deep grooves or slots 51 in the block 52 carried on the cross rod 53. In order to lock the keys in inner or outer position, there is provided a locking plate 54 carried on the outer face of said block 52 and adapted to engage in the inner notch 56 or the outer notch 57 of the key 50. As is obvious, when the key is in outer position, as shown by the full lines, the latch bar 34 is free to reciprocate, as has been explained. On the other hand when the key is moved to the inner position, as shown by the dotted lines of Fig. 2, the latch bar is held against reciprocation and any combination of setting bars that have been depressed must remain depressed so long as the keys 50 associated with their latch bars remains in locking position.

It is obvious that various changes and modifications may be made to the details of construction without departing from the general spirit of the invention as claimed.

I claim as my invention:

1. In a perforator, the combination of setting bars each provided with an abutment shoulder and a cam edge; a latch bar; means for actuating the setting bars whereby said cam edge engages and forces back the latch bar to permit the latter to engage over said shoulders; yieldable means for moving the latch bar to unlatching position; and means for preventing the operation of the yieldable means.

2. In a perforator, the combination of a

plurality of setting bars each provided with an abutment shoulder and a cam edge; punches set by the setting bars respectively; a latch bar provided with latching shoulders; means for operating the setting bars whereby said cam edge engages and forces back the latching shoulders to permit the latter to engage over said abutment shoulders; yieldable means for moving the latching bars to unlatching position; and means for holding the latching bars in latching position.

3. In a perforator, the combination of a plurality of setting bars each provided with a projection provided with an upper shoulder, a lower cam face, and an upper cam face connecting the lower cam face with the shoulder; a punch adapted to be set by each setting bar; a card support coöperating with the punches; a latch bar provided with latching shoulders adapted normally to yieldably engage under said lower cams; a carriage; means carried on the carriage for individually operating the setting bars whereby said lower cam face engages and forces back said latching shoulders to permit the latter to engage over the upper shoulder of the actuated setting bar, and to release any previously actuated setting bar; yieldable means mounted on the carriage for moving the latching bars to unlatching position; and settable locking means for locking the latching bars in latching position.

35 4. In a perforator, the combination of a plurality of rows of setting bars each provided in one edge with an upper and lower recess forming therebetween a projection provided with an upper shoulder, a lower cam face and an upper cam face connecting the lower cam face with the shoulder; a punch adapted to be actuated by each setting bar; a card support coöperating with the punches; a latch bar slideable transversely of the setting bars of each row and provided with latching shoulders adapted normally to engage in said lower recesses; a carriage; means carried on the carriage for individually operating the setting bars, whereby said lower cam face engages and forces back said latching shoulders to permit the latter to engage over the upper shoulder of the actuated setting bar, and to release any previously actuated setting bar; yieldable means mounted on said carriage and adapted to engage said latching bars to move them to unlatching position; and individually settable locking means for locking the latching bars in locking position.

60 5. In a perforator, the combination of setting bars each provided with a projection provided with a lower cam face, an upper shoulder, and an upper cam face connecting said upper cam face and shoulder; a latch bar; and means for actuating the setting

bars whereby said lower cam face engages and forces back the latching bar to permit the latter to engage over the upper shoulder of the actuating setting bar and to release the latch bar from the upper shoulder of any previously actuated setting bar whereby the upper cam face of such previously actuated setting bar engages and forces back the latch bar surely to permit the entire release of such previously actuated setting bar.

6. In a perforator, the combination of setting bars each provided in one edge with an upper and a lower recess forming therebetween an upper cam face merging into said shoulder and said lower cam face; a latch bar provided with latching shoulders normally engaging in said lower recess; and means for actuating the setting bars whereby said lower cam face engages and forces back the latching shoulder to permit the latter to engage over the upper shoulder of the actuated setting bar, and to release the latching shoulder from the upper shoulder of any previously actuating setting bar, whereby the upper cam of such bar engages the latching shoulder which was released from the upper shoulder of such bar and forces back the latching bar to permit the entire release of such previously actuated setting bar.

7. In a perforator, the combination of setting bars each provided with an abutment shoulder and a cam edge; a latch bar; means for actuating the setting bars whereby said cam edge engages and forces back the latch bar; means for yieldably moving the latch bar to unlatching position; a fixed block at one end of the latch bars and provided with key receiving slots and a locking plate; and locking keys in said slots and provided with a pair of notches for receiving said locking plate, to selectively lock said latch bars against endwise unlatching movement.

8. In a perforator, the combination of setting bars each provided with an abutment shoulder and a cam edge; a latch bar; means for actuating the setting bar whereby said cam edge engages and forces back the latch bar; a carriage; a pivoted bracket carried on said carriage and spring pressed toward one end of the latch bars; and a roller carried on said bracket and adapted to engage the end of the latch bar and move the latch bar to unlatching position.

9. In a perforator, the combination of setting bars each provided with an abutment shoulder and a cam edge; a latch bar; means for actuating the setting bar whereby said cam edge engages and forces back the latch bar; a carriage; a pivoted bracket carried on said carriage and spring pressed toward one end of the latch bars; a roller carried on said bracket and adapted to engage the end of the latch bar and move the latch bar to

unlatching position, and means for at will preventing the unlatching movement of the latch bar.

10. In a perforator, the combination of a plurality of rows of upwardly spring pressed flat vertically slidable setting bars, each provided in one edge with an upper and a lower recess forming therebetween a rounded projection provided with an upper shoulder and a lower slanting cam face; a punch adapted to be depressed by each setting bar; a card support beneath the punches; a latch bar yieldably slidable transversely of the setting bars of each row and provided with latching shoulders adapted normally yieldably to engage in said recesses; a carriage; means carried thereon for individually depressing the setting bars, whereby said cam face engages and forces back all of said latching shoulders to permit the latter to engage over the upper shoulder of the setting bar being depressed and to release any previously depressed setting bar; a roller yieldably mounted on said carriage and adapted to engage one at a time, one end of each latching bar to move it to unlatching position; and individually settable locking keys for locking the latching bars in latching position.
30. 11. In a device of the character described, the combination of setting members; anchoring means for holding the setting members set; means for causing said anchoring means to be released; and means for rendering said releasing means inoperative position during the time that the setting members are usually brought into set position.

12. In a device of the character described, the combination of setting members adapted to be individually set and when set to release a previously set member; means for causing said set members to be released, and means for at will rendering said releasing means inoperative during the time that the setting members are usually moved to set position.

13. In a device of the character described, the combination of groups of setting members, the setting members being adapted to be individually set, and when set to release a previously set member; means associated with each group and adapted to bring about such release of the previously set member and to hold the setting member set; and means for at will holding certain of said releasing means inoperative.

14. In a device of the character described,

the combination of groups of setting members, the setting members being adapted to be individually set, and when set to release a previously set member; means associated with each group and adapted to bring about such release of the previously set member and to hold the setting member set; and means for holding certain of said releasing means inoperative while the others of said devices are operative.

15. In a device of the character described, the combination of groups of setting members, the setting members being adapted to be individually set, and when set to release a previously set member; means associated with each group and adapted to bring about such release of the previously set member and to hold the setting member set; and means for holding certain of said releasing means inoperative throughout all phases of the operation of the machine.

16. In a device of the character described, the combination of groups of setting members, the setting members being adapted to be individually set, and when set to release a previously set member; means associated with each group and adapted to bring about such release of the previously set member and to hold the setting member set; and means for at will holding certain of said releasing means inoperative while the others of said releasing means are operative throughout all phases of the operation of the machine.

17. In a device of the character described, the combination of setting members each provided with a shoulder, a cam face inclining toward and meeting said shoulder and a cam surface meeting and inclining from said cam face; a yieldable latch device provided with portions adapted to engage said shoulder, face and surface; and means for actuating the setting members to cause said cam surface to engage said portion to permit the latter to engage said shoulder and release said device from the shoulder of any previously actuated, whereby said cam setting member of such previously actuated member engages and forces back said latch device surely to permit the entire release of such previously actuated member.

WILLIAM W. LASKER.
